UNITED STATES PATENT OFFICE.

GEORGE H. PAGE, OF RICHMOND, MISSOURI.

LIFTING-JACK.

1,327,685.

Specification of Letters Patent. Patented Jan. 13, 1920.

Application filed February 21, 1916. Serial No. 79,589.

To all whom it may concern:

Be it known that I, GEORGE H. PAGE, a citizen of the United States, residing at Richmond, in the county of Ray and State 5 of Missouri, have invented certain new and useful Improvements in Lifting-Jacks, of which the following is a full and exact specification.

The present invention relates to lifting jacks for wagons and the like, and aims to provide an improved arrangement and construction having provision for quick and convenient adjustment of the lifting lever to various heights whenever the device is 10 to be used under circumstances requiring a slight change in the fulcrum position of the lever. To this end the invention provides a jack construction comprising a standard having a vertical series of fulcrum shoulders with any one of which the lever may be 15 quickly associated, together with a suitable keeper member of an improved type for co-operating with the standard to hold the lever with its fulcrum in proper position 20 during the jacking operation.

With this general object in view as well as various minor objects as will hereinafter appear, the invention will now be described with reference to the accompanying drawing 30 illustrating one form of embodiment of the improvements, after which those features and combinations deemed to be novel will be set forth and defined in the appended claims.

35 In the drawing—

Figure 1 is a side elevation of the jack, with one end portion of the lifting lever broken away;

Fig. 2 is a horizontal section taken along 40 the line II—II of Fig. 1; and

Fig. 3 is a vertical section taken along the line III—III of Fig. 1.

Referring to the drawing in detail, the improved jack is illustrated as comprising a 45 standard made up of a pair of spaced upright members 2, 2, and secured in this relation by means of a spacing block 3 at the top and a spacing block 4 at the bottom, a base member 5 of suitable width being also 50 provided at the bottom for supporting the jack in proper vertical position. The front edges of the uprights 2 are formed with a vertical series of shoulders 6 arranged in pairs for supporting the lever 7 and its 55 pivot bolt 8 in various vertical positions; these front edges of the uprights are rein-

forced by suitable metal strips 9, and the load-supporting end of the lever is also properly reinforced by a similar wear strip 10. The rear end of said lever is formed 60 with a series of notches 11 adapted to be engaged by one end of a link 12 pivoted at 13 between the uprights 2, and having a loop portion 14 for embracing the notched portion of the lever 7.

The rear edges of the uprights 2 are formed with a series of vertically spaced notches 15, also arranged in pairs for engagement by a keeper bolt 16 which is supported in the rear ends of a pair of strap 70 links 17, the front ends of which are carried by the opposite ends of the pivot bolt 8. The length of the links 17 is such as to retain the pivot bolt 8 securely in shouldered position during the jacking operation while at the 75 same time permitting said links to be swung upward to disengage the keeper bolt from its notch in adjusting the lever to a different elevation. Since the arrangement of shoulders described requires the uprights 2 to be 80 of greater width from top to bottom, the angles of the operative edges of the notches are arranged accordingly, being such as to bring said edges always at approximately right angles to lines joining them to the 85 corresponding shoulders 6.

Provision is also made for a slight further adjustment of the lever, intermediate the adjustments above described. This is accomplished by forming a series of bolt openings 18 in the lever for adjustment of the bolt 8, whereby the latter's position may be 90 changed either transversely or longitudinally with reference to the lever and thus altering the fulcrum position of the latter 95 for any one shouldered position of the bolt.

It will thus be apparent that a simple and convenient construction has been devised for carrying out the desired objects of the invention. The lever's position may be 100 quickly changed to suit any ordinary height of wagon axle or other part to be lifted by simply raising the links 17 and bolt 16 along with the lever and shifting the bolt 8 to the proper shoulder 6, after which the 105 keeper bolt 16 will, on releasing the links 17, drop into the corresponding pair of notches 15 and securely retain the lever with its bolt 8 in proper working position. Should any further minor adjustment of the 110 lever be needed or desired, either transversely or longitudinally of the lever, this

may be attained by proper adjustment of the bolt 8 relatively to the bolt openings 18. When the lever has been operated it will be held in depressed position by means of the link 12 in the manner illustrated. A strong, durable and inexpensive construction is thus provided, and while the preferred form of embodiment of the improvements has been herein set forth, the right is reserved to such 10 formal changes and modifications as may fairly fall within the scope of the appended claims.

Claims:

1. A lifting jack comprising a standard 15 provided with a vertically arranged series of shoulders and a corresponding series of notches at the rear of said shoulders, a lifting lever provided with a pivot bolt adapted to be supported on any one of said shoulders, and a keeper member carried pivotally by said bolt and coöperating with said notches for retaining said bolt in shouldered position.
2. A lifting jack comprising a standard 25 provided with a vertically arranged series of shoulders and a corresponding series of notches at the rear of said shoulders, a lifting lever provided with a pivot bolt adapted to be supported on any one of said shoulders, and means for retaining said bolt in shouldered position comprising a link pivoted to the bolt and carrying a second bolt movable into engagement with one of said notches.
3. In a lifting jack, a standard comprising a pair of spaced uprights each formed with a vertical series of shoulders and a corresponding series of notches at the rear of said shoulders, said shoulders and notches

being arranged in pairs, a lifting lever 40 mounted between said uprights and provided with a pivot bolt adapted to be supported on any one of said pairs of shoulders, and means for retaining said bolt in shouldered position comprising a pair of 45 links pivoted at their front ends to said bolt and supporting at their rear ends a second bolt movable into engagement with a pair of said notches.

4. A lifting jack comprising a standard 50 gradually increasing in width from top to bottom and provided with a vertically arranged series of shoulders and a corresponding series of notches at the rear of said shoulders, a lever provided with a pivot bolt 55 adapted to be supported on any one of said shoulders, and means for retaining said bolt in shouldered position comprising a link pivoted to said bolt and carrying a second bolt movable into engagement with one of said 60 notches, the operative edges of said notches being arranged at approximately right angles to lines joining them with their corresponding shoulders.

5. A lifting jack comprising a standard 65 provided with a vertically arranged series of shoulders and a corresponding series of notches at the rear of said shoulders, a lifting lever provided with a pivot bolt adapted to be supported on any one of said 70 shoulders, and keeper means adjustable vertically in unison with said lever, said keeper means comprising a yoke embracing the standard and coöperating with said notches for retaining said bolt in shouldered position.

GEORGE H. PAGE.
